UNITED STATES PATENT OFFICE.

MAX R. KOERNER, OF ELMWOOD, CONNECTICUT, ASSIGNOR TO THE A. J. BEATON MANUFACTURING COMPANY, OF NEW BRITAIN, CONNECTICUT, A CORPORATION OF CONNECTICUT.

FLOOR OR CEILING PLATE.

1,372,518.

Specification of Letters Patent. Patented Mar. 22, 1921.

Application filed October 22, 1920. Serial No. 418,722.

To all whom it may concern:

Be it known that I, MAX R. KOERNER, a citizen of the United States, residing at Elmwood, in the county of Hartford and State 5 of Connecticut, have invented certain new and useful Improvements in Floor or Ceiling Plates, of which the following is a specification.

This invention relates to a floor or ceiling plate. I have a number of motives in view among the principal ones of them being the provision of an article of this character which is capable of exceedingly inexpensive construction, which possesses the 10 maximum strength and which also consists of a very few parts. As a matter of fact the plate itself outside of the holding springs which are usual in this kind of article, and the pivot, preferably comprises 15 but two parts. Obviously therefore the device can be easily, inexpensively and quickly made.

In the drawings accompanying and forming part of the present specification I have 20 shown in detail a form of embodiment of the invention which to enable those skilled in the art to practise the same will be set forth fully in the following description. The novelty of the invention will be included in the claims succeeding said description. I am not restricted to this exact showing. I may depart therefrom in several particulars within the scope of the invention defined by the claims.

35 Referring to said drawings:

Figure 1 is a bottom plan view of a floor or ceiling plate involving the invention.

Fig. 2 is a detail in section of the rear or hinge portion of the plate.

40 Fig. 3 is a detail in section of a portion of one of the sections or halves of the plate.

Fig. 4 is a similar view of the latch portion.

Fig. 5 is a fragment of the inside of one 45 of the sections.

Like characters refer to like parts throughout the several views.

These floor or ceiling plates are generally applied to steam or water pipes, for finishing purposes. They fit around the pipes adjacent the ceiling or the floor and customarily bear against the latter. As shown the plate comprises two semi-annular sections 2 and 3 usually of sheet metal. Each

of the sections is of a half circle, their radial 55 straight ends being in abutment as shown in Fig. 1, when the plate is closed, for instance around a pipe.

The sections 2 and 3 are furnished along their inner edges with flanges as 4 and 5 which are integral with the respective semi-circular sections. The flange 4 is shown as having at its back end the rearwardly-extending and practically radial extension 6. The flange 5 at its back end is shown as having the rearwardly-extending obtuse angular extension 7 integral therewith and overlying the extension 6, the extensions 6 and 7 being jointed to each other as by the pivot 8, which may as is common, consist of a 70 rivet held in place by heading.

The flange 5 has at its front end as shown the forward integral projection 9 constituting a convenient catch, to be engaged as I will later set forth, by a latch associated as 75 shown with the section 2. The flange 4 as illustrated is furnished at its front end with an extension 10 which is laterally-forwardly bowed somewhat between its ends, and which has a notch or slot 11 in its under 80 surface to receive the catch 9. This latching portion 10 it will be seen extends laterally beyond the front end of the section 9. The two sections 2 and 3 are assumed to be latched together in Fig. 1.

To open the ring the following procedure 85 may be adopted. The sections 2 and 3 will be relatively tipped sufficiently to carry the catch 9 out of the notch 10 at which time the sections can be easily spread apart, 90 swinging on the pivot 8. The under side of the latching portion 10 is beveled or rounded off as at 12, the beveled surface engaging the catch 9 as the sections are closed, thereby camming the section so that movement of them sufficiently is insured to cause the entrance of the catch 9 into the notch 11 as the sections are snapped closed.

The flanges 4 and 5 have between their ends transversely elongated slots 13 to receive the legs of branches of bowed springs as 14 the transverse portions of the springs bearing against the outer surfaces of the flanges 4 and 5 respectively and the legs thereof extending into the opening presented jointly by the sections 2 and 3, the result being that when the ring is closed upon a pipe or something of a similar nature it will 100 105

be yieldingly engaged by the free portions of the two springs. The slots 13 to which I have referred may in part be formed in the lugs 15 extending in pairs from the respective flanges 4 and 5.

What I claim is:

1. A floor or ceiling plate comprising two semi-circular sections of sheet metal provided along their inner edges with semi-circular integral flanges, the rear end portions of the flanges having integral rearwardly extending extensions pivotally connected together, and the front end portions of the sections having means to releasably connect the sections together.

2. A floor or ceiling plate comprising two semi-circular sections of sheet metal provided along their inner edges with semi-circular integral flanges, the rear end portions of the flanges having integral rearwardly-extending extensions pivotally connected together, and the front end portions of the flanges having integral portions to releasably connect the two sections together at the front end of the plate.

20

25

In testimony whereof I affix my signature.

MAX R. KOERNER.
